Application April 26, 1938, Serial No. 204,403

5 Claims.

(Cl. 60—97)

This invention relates to the construction of a prime-mover composed of a plurality of internal-combustion engines of the crankless type arranged to transmit power to a common take-off so as to form a composite power-unit. Under the designation "engines of the crankless type" are included all engines having their cylinders arranged parallel to the power shaft actuated by said pistons.

A main purpose of the invention is the production of power units of the least possible bulk and weight relatively to their power, it being known from theoretical considerations and confirmed by experience in the art that subdivision of the essential organs (e. g. cylinders), of an engine into a plurality of smaller organs having the same total output tends to reduction of total weight. Likewise, a composite engine, comprising a plurality of component engines coupled together, will be lighter than a similar single engine of the same power.

A power unit consisting of component engines combined according to the invention presents also the advantage that one or more of the components may be detached, or allowed to remain idle, for purposes of inspection, adjustment, or repair, or to economize fuel, while the remaining components continue to be effective for supplying power to the common power take-off.

A further purpose and advantage of the construction is that the power take-off of the unit may have any desired ratio of rotative speed relatively to the frequency of reciprocation of the pistons of the component engines (such ratio being arranged in the gearing essential to the construction of the combined unit), whereby in most cases the use of any gearing between the power-take-off of the prime-mover and the driven machine can be avoided.

Having these characteristics, prime-movers constructed according to the invention are specially applicable to the propulsion of aircraft.

In a particular application of the invention by means of component engines of the opposed-piston crankless type, as described in the following specification, each engine is constructed with two engine shafts in longitudinal alignment with each other (each of the shafts being separately geared to the common power shaft of the composite unit), instead of having only a single power-shaft as hitherto. An engine so constructed is the subject of an application divisional from the present case.

In the accompanying drawings illustrative of the invention:

Fig. 1 is a longitudinal section on the broken line 1, 1 of Fig. 2, of a power unit constructed according to the invention.

Fig. 2 (which shows only the moving parts of 5 the unit), is a cross-section on the line 2, 2 of Fig. 1.

These views are to some extent diagrammatic, serving to illustrate broadly the principle of the invention.

Fig. 3 is a half cross-section of a component engine showing details differing in some respects from those indicated in Figs. 1 and 2, and to a larger scale.

Fig. 4 is a longitudinal view of a complete 15 power-unit, being partly in section and partly in external elevation, and illustrates the application in the invention of crankless engines of the opposed-piston type.

Fig. 5 is a half cross-section, with details simplified for the sake of clearness, taken on the line 20 5, 5 of Fig. 4.

The same reference numeral is applied to designate the same part wherever shown in the various figures.

25 As shown in Figs. 1 and 2 each of the six component crankless engines of the power unit comprises an engine-shaft 11 on which is mounted a slant, swash-plate or wobble-plate, 12, caused to rotate with the shaft 11 by the action of the pistons 13 reciprocating in the cylinders 14. In the preferred construction shown, which is not however essential to the invention, the pistons 13 drive the shaft 11 through the medium of a pair of bearing slippers 15 mounted in the crosshead 30 16 which is rigidly attached to the piston by means of the piston rod 17. The shaft 11 and plate 12 are supported against the axial thrust exerted by the piston 13 by means of the thrust bearing 18. The shaft 11 is also supported in 35 journal bearings 20, 20a.

As shown in Figs. 1 and 2 each component engine has three pistons 13, reciprocating in three cylinders 14, and the complete power unit consists of six of such engines arranged about the 40 common centre-line C, which is the axis of the power take-off of the unit. Any other desired numbers of component engines, and of cylinder-and-piston elements in each engine, arranged in a similar manner may be used.

45 Each component engine is geared to the common power take-off of the unit (such power take-off being shown in Fig. 1 as a hollow stub-shaft 21 mounted in bearing 22), by gear wheels 23 rotating with their respective shafts 11 and engaging with a main gear wheel 24 mounted on

the stub shaft 21. In the application of the invention to the power units of air-craft the aero-propeller may be mounted on the extension 25 of the stub-shaft 21, and (the hollow extension 25 being arranged to extend through the boss of the propeller), a gun, (not shown), may be located wholly or partially within the space 26 enclosed by the component engines so as to be adapted to fire through the hollow shaft 21 and propeller boss.

Any usual form of gearing or power-transmission (mechanical, hydraulic or electric), may be used for gearing the engine-shafts 11 to the power take-off 21, alternatively to the gear transmission shown.

The moving parts of the composite unit may be contained and supported in common in a single casing, but preferably, as shown in Fig. 3, each component engine, comprising all the moving parts shown in Fig. 2 together with thrust and journal bearings as 18, 20 and 20a, is constructed as a self-contained unit having a separate frame. In the half-section, Fig. 3, the frames 31, 31a, 31b of three of such engines are shown arranged in a semi-circle around the axis C, such frames being adapted to be bolted to the other frames forming the composite unit, on radial planes indicated by the lines CA, CB, CC, CD, the external portions of the frames 31, including the cylinders, forming a complete external covering throughout their length for the composite unit including the power take-off shaft 21. The enclosure of the composite power unit is completed by end-casings, as 34 Fig. 1.

In the application of the invention to compression-ignition engines, shown in Figs. 4 and 5, each of the component engines (as shown in the upper portion of Fig. 4, which is a longitudinal section on the line 4, 4 of Fig. 5), comprises two engine shafts 11, 11a, and a plurality of cylinders 14, each containing two pistons 13, 13a, respectively engaging with the two swash plates or slants 12, 12a (severally mounted on the shafts 11, 11a), by means of the slipper bearings 15, 15a mounted in the cross-heads 16, 16a, as already described in connection with Figs. 1 and 2. The term "slants" will be used hereinafter to designate members 12, 12a. The shafts 11, 11a are respectively geared, as by pairs of gear-wheels 23, 24 and 23a, 24a, to the power take-off shaft 21 of the composite unit, so as to be caused to rotate at equal speeds and in fixed angular relation to each other. The slants 12, 12a are thus caused to rotate in fixed, and approximately opposite, mutual phase relationship, and the pistons 13, 13a to reciprocate in approximately opposite phases.

Individual frames 31, 31a, etc., comprising the cylinders may be provided for the several engines as shown, these frames being bolted or otherwise attached together throughout their lengths and enclosing the power take-off shaft as already described in connection with Fig. 3.

Each component engine is thus a modified form of the opposed-piston internal-combustion engine described in United States patent of Re-issue No. 17,273. While it has hitherto been the practice in the construction of engines of this type to mount the two slants rigidly upon a common shaft, whereby they were necessarily in fixed phase relation with each other, the same fixed relationship of phase is secured according to the present invention by the gearing of the two separately mounted shafts 11, 11a, to the power take-off shaft 21, of the composite unit.

The fuel injectors, especially those of the inner

cylinders of the unit, are conveniently inserted into their combustion spaces between the adjacent ends of the two shafts 11, 11a, with their axes on radial lines intersecting the common axis of the shafts, a so-called "long-reach" injector being suitable for the purpose. The injectors 36a (see Fig. 5) of the outer cylinders of the unit may of course be of the usual short type fitted in the usual way. The openings for the insertion of both classes of injectors are shown at 37, 37a in the lower portion of Fig. 4 (external view).

In the same figure are shown the external openings 41 for discharge of the exhaust gases from the exhaust chambers 42, and openings 43 for intake of scavenge air into the scavenge chambers 44. The cylinders communicate with the chambers 42 and 44 respectively through exhaust ports 45 and scavenge ports 46, arranged peripherally around each of the cylinders in the manner usual in engines of the opposed-piston type. The scavenge air may be supplied by a fan 51, preferably gear driven from the shafts 11a, the delivery ports 52 of the fan-casing 53 being connected to the intake openings 43 by suitable conduits or casings not shown. The exhaust chambers 42, and scavenge chambers 44 may be common to the whole power unit, or alternatively separate exhaust chambers and scavenge chambers, with separate exhaust and scavenge openings, may be provided for each engine.

It is to be understood that the mode of arrangement of the scavenge and exhaust chambers and ports which is described in the preceding paragraph is applicable not only to the form of construction of the individual engines with paired shafts as shown in Figs. 4 and 5, but also to forms of construction in which each engine has only a single shaft.

The other usual accessories of internal-combustion engines such as fuel-pump 54, circulating water-pump 55, necessary lubricating and starting mechanisms, and the like, are preferably coupled, either directly or through gearing, to the shaft 21 of the combined unit.

The gearing by which each of the engine shafts 11, 11a, transmits power to the common power take-off, is preferably so arranged that each engine shaft can be readily disconnected from the transmission, and thereby detached, or allowed to remain idle while other units continue to be effective for supplying power. An example of such an arrangement is shown in connection with the shaft 11 in Fig. 4. As shown in this figure, the thrust bearing 18 and outer bearing 20 of the engine shaft 11 are supported in a spider 61 attached to the engine frame 31. The portion of the shaft 11 extending beyond the bearing 20 is formed with splines 62. In the end-casing 34 of the power-unit is fixed a shaft 63. The sleeve 64 is rotatably supported at its outer end on the shaft 63, and at its inner end fits upon the shaft 11 and slidably engages the splines 62. The gear wheel 23 is mounted by means of a feather or splines upon the sleeve 64 so as to be slidable thereon, and the sleeve is formed with a circumferential groove 65, adapted to be engaged by a collar and lever (not shown) so as to be readily moved in the axial direction at will.

It will be understood that when the sleeve 64 stands in engagement with the splines 62 of the shaft 11, as shown by full lines in the figure, the sleeve and gear wheel are compelled to rotate with the shaft 11 which is then enabled to transmit power to the shaft 21. When, on the other

hand, the sleeve 64 is moved axially by means of its collar to the position shown by dotted lines, its inner end is detached from the shaft 11 which is thereby rendered idle. The sleeve 64 then continues to run upon the shaft 63 being driven by the engagement of gear 23 to the main gear-wheel 24 of the power unit.

The mutually-engaging splines of the shaft 11 and sleeve 64 are so formed that the shaft and sleeve can only be put into engagement in one angular position, thus ensuring that the correct phase relationship of the shafts 11 and 11a is maintained whenever the engine is put into operation.

Similar means of disengagement being provided for the shaft 11a, as shown, and engine-casing 31, Fig. 4, being constructed as a self-contained section attached to the casings of the other engines of the power unit, as explained in connection with Fig. 3, it will be understood that effecting the disengagement of both shafts and disconnecting the casing 31 from the end casings 34 the component engine comprising all the moving parts and the casings 31, spiders 61 and bearings may be removed without affecting the combination of the remainder of the power unit. Alternatively the engine may be left in position, and allowed to remain idle while the remainder of the composite unit continues to be operative.

By the provision (e. g. in air-craft and high-powered boats) of such facilities for the removal, or laying-off, of the component engines, the invention provides in a single composite power unit a degree of reliability which can only be secured otherwise by the installation of a multiplicity of separate power units. The latter arrangement involves of course the use of several of such separate engines to enable any one of them to be laid off without serious diminution of the available power. Also the location of a multiplicity of engines in most cases presents considerable difficulty and inconvenience. Moreover their supports and enclosures necessarily add to the total weight of the craft.

The construction which is the subject of the present invention enables all the principal advantages of subdivision of a power-plant to be secured, together with the evident convenience of centralizing the plant, and with a great diminution of the necessary weight.

It will be evident from the drawings, and more especially from Fig. 5, that the total sectional area of the cylinders of a composite engine constructed according to the invention, bears a much larger ratio to the total cross-sectional area of the power-plant, than is the case in the usual modes of construction. Since the total sectional area of the cylinders is an approximate measure of the power of an engine, it is apparent that a large saving of bulk relatively to power will be effected by the application of the invention.

In the arrangement of the gearing of composite power units as hereinbefore described, the gearing is preferably so arranged that no two engine cylinders in the whole unit are in the same phase of their cycles. The stresses imposed on the common power take-off elements are thereby minimized, and furthermore the number of torque impulses exerted by the unit is thereby

increased to the maximum possible, whereby smooth operation of the unit is assured.

Although certain specific embodiments of the invention have been particularly shown and described it will be understood that it may be modified in various other ways without departing from the spirit or scope of the invention, as expressed in the following claims:

What I claim is:

10. 1. In a power unit comprising a plurality of opposed-piston engines each having a group of parallel cylinders, a pair of opposed pistons reciprocating in each of said cylinders, and two engine shafts in axial alignment each of said shafts being actuated by the totality of pistons located in corresponding ends of said cylinders, a power take-off shaft positioned parallel to said engine shafts and arranged to be driven by the totality of the engine shafts located at corresponding ends of said engines.
15. 2. In a power unit comprising a plurality of two-stroke internal combustion engines, having parallel cylinders, pistons reciprocating in said cylinders, an engine shaft for each engine actuated by the pistons of said engine and parallel to said cylinders, individual frames for said engines containing said cylinders and attached together throughout the length of said cylinders so as to form a scavenging air chamber common to all
20. 30. the cylinders of the unit and enclose a power take-off shaft positioned parallel to and actuated by the said engine shafts.
25. 3. In a power unit comprising a plurality of two-stroke internal combustion engines, having parallel cylinders, pistons reciprocating in said cylinders, an engine shaft for each engine actuated by the pistons of said engine and parallel to said cylinders, individual frames for said engines containing said cylinders and attached together throughout the length of said cylinders so as to form an exhaust chamber common to all the cylinders of the unit and enclose a power take-off shaft positioned parallel to and actuated by the said engine shafts.
35. 4. In a power unit comprising a plurality of two-stroke internal combustion engines, having parallel cylinders, pistons reciprocating in said cylinders, an engine shaft for each engine actuated by the pistons of said engine and parallel to said cylinders, individual frames for said engines containing said cylinders and attached together throughout the length of said cylinders so as to form a chamber for circulation of cooling fluid common to all the cylinders of the unit and enclose a power take-off shaft positioned parallel to and actuated by the said engine shafts.
40. 5. In a power unit comprising a plurality of two-stroke internal combustion engines, having parallel cylinders, pistons reciprocating in said cylinders, an engine shaft for each engine actuated by the pistons of said engine and parallel to said cylinders, individual frames for said engines containing said cylinders and attached together throughout the length of said cylinders so as to form an exhaust and scavenging-air chambers common to all the cylinders of the unit and enclose a power take-off shaft positioned parallel to and actuated by the said engine shafts.
45. 60. 65. 70.

ANTHONY GEORGE MALDON MICHELL.
